UNITED STATES PATENT OFFICE.

JESSIE E. PRICE, OF LOS ANGELES, CALIFORNIA.

SHOE-HEEL.

1,269,958.

Specification of Letters Patent. Patented June 18, 1918.

Application filed May 21, 1917. Serial No. 170,026.

To all whom it may concern:

Be it known that I, JESSIE E. PRICE, a citizen of the United States, residing at Los Angeles, in the county of Los Angeles and State of California, have invented a new and useful Shoe-Heel, of which the following is a specification.

This invention relates to a cushion heel for boots, shoes and the like.

- 10 It is the object of this invention to provide a cushion heel embodying a tread surface formed partly of a resilient material, such as rubber, and partly of a non-resilient material such as wood or leather, so as to 15 produce a heel having greater wearing qualities than one formed with an entire rubber surface and at the same time equip the heel with a gripping or non-slipping surface.
- 20 A further object is to provide the heel with a resilient portion which is reinforced with fabric, fiber or the like, to enhance its wearing qualities.

Another object is to provide resilient tread 25 section of such shape that it will interlock with the contiguous edge of the non-resilient tread section so that fastening devices, such as screws or nails, need not be placed through the resilient tread section.

30 Other objects will appear hereinafter.

The invention is illustrated in the accompanying drawings, in which:

Figure 1 is a view of the heel in longitudinal section.

35 Fig. 2 is a plan view of same.

Figs. 3 and 4 are plan views showing the arrangement of the resilient tread section at different points on the heel.

More specifically 5 indicates the shank of 40 the shoe to which is attached a lift 6 in the usual manner. This lift may be formed of wood or built up of leather. In carrying out my invention I provide a sheet 7 of resilient material conforming to the lower 45 face of the lift which sheet is reinforced by a horizontal layer of fabric 8. Any suitable number of layers or strips of fabric may be employed, three of such layers being here shown as incorporated in the sheet, 50 and these layers may consist of any suitable material such as cloth, yucca, or other fibrous substance.

Covering the major portion of the sheet 55 is a non-resilient tread section 9 which may be formed of wood, leather or other suitable material and constitutes the forward tread

face of the heel. The rear portion of the tread section 9 is formed with an incurved arcuate face forming a crescent shaped edge curved in a direction opposite that of the rear portion of the heel. The space thus formed between the rear edge of the heel and the non-resilient tread section is filled by a resilient tread section 10 the bottom face of which extends flush with the tread section 9 and the outer or side face of which conforms to the vertical edge of the lift. The edge of the resilient section 10 adjacent the non-resilient section 9 is formed on an outward arcuate curve to conform to the section 9. A portion of the tread section 9 thus extends beyond each side of the intermost portion of the section 10, forming an interlocking joint which tends to hold the section 10 against side- 75 wise displacement. This section 10 is reinforced by fabric strips 11 which are here shown as arranged vertically therein, the fabric 11 being designed to reinforce the rubber against wear as well as to retain it 80 in shape. The fabric in wearing down with the rubber presents a rough surface on the tread face thereof which serves to give the resilient tread section a non-slipping character.

As a means for fastening the tread members on the lift, the sheet 7 and the non-resilient tread section 9 are cemented together and is thus formed to constitute an article of manufacture adapted to be marketed and employed in re-heeling boots, 90 shoes, slippers and the like. In attaching the tread to the lift, the sheet 7 is cemented to the latter and if desired nails or pegs may be driven through the non-resilient tread 95 section and the sheet 7 into engagement with the lift. By so doing, the sheet 7 will be rigidly clamped between tread section 9 and the lift. If it is desired to utilize the resiliency of the sheet 7 so as to form a cushion tread throughout the tread, the section 9 is formed with perforations 12 terminating in counterbores 13 through which screws 14 are passed and screwed into the lift as shown in Fig. 1. The heads of the screws 100 105 being countersunk permit a compression movement of the non-resilient tread section which is thus cushioned on the sheet 7. The screws 14 may be disposed at any convenient points throughout the tread section but 110 it is desirable that a screw be disposed adjacent each termination of the arcuate rear

end of the tread section so as to provide fastenings adjacent the ends of a resilient tread section.

In carrying out the invention, the resilient tread section is formed with a tread surface much smaller in area than that of the non-resilient tread section and is disposed in such position on the heel as to receive the impact on contact of the heel with a surface according to the habit of the wearer in setting the foot on the ground. For example, in some cases the resilient tread section is disposed directly across the rear edge of the heel as shown in Fig. 2, and in other instances it may be positioned to the right or left of the longitudinal center of the heel as shown in Figs. 3 and 4.

By reinforcing the rubber sheet and tread portions with fabric or the like, the wearing quality and durability of this portion is much enhanced, and furthermore a secure engagement between the tread and the lift is effected by reason of the fastenings passing through and engaging the fabric. The tread section 9 is formed of a material not liable to slip and thus frees the heel from the objection common to cushion heels having a tread surface entirely of rubber.

I claim:

1. In a cushion heel, the combination of a lift, a sheet of resilient material on the under side of the lift, a resilient tread member formed on the edge of said sheet, reinforcing fiber in said tread member, and a non-resilient tread member overlapping the sheet and having an inwardly curved cut-out portion on its edge partly encircling the edge of the resilient tread member.

2. In a cushion heel, a lift having an outwardly curved outer edge, a sheet of resilient material covering the underside of said lift, a resilient tread member integral with said sheet and arranged at a point on the edge of the sheet with an outwardly curved outer edge formed in continuation of the lift, reinforcing fiber in said tread member and a non-resilient tread section extending over the sheet having a cut-out portion on its edge conforming at its margin to the inner edge of the resilient tread member. 40

3. In a cushion heel, a lift having an outwardly curved outer edge, a sheet of resilient material covering the underside of said lift, a resilient tread member integral with said sheet and arranged at a point on the edge of the sheet with an outwardly curved outer edge formed in continuation of the lift and having an outwardly curved inner edge at its juncture with the sheet, reinforcing fiber in said tread member, and a non-resilient tread section extending over the sheet having a cut-out portion on its edge conforming at its margin to the inner edge of the resilient tread member. 55

4. A cushion heel, comprising, a lift, a sheet of resilient material on the under side of said lift, a resilient tread member on the edge of said sheet and having its outer edge formed in continuation of the edge of the lift, fabric reinforcement strips throughout 70 said resilient sheet and tread member, and a non-resilient tread member covering said resilient sheet and having an outer edge conforming to the edge of the lift on the opposite sides of the resilient tread member.

JESSIE E. PRICE.
